UNITED STATES PATENT OFFICE.

WINTHROP K. HOWE, OF ROCHESTER, NEW YORK, ASSIGNEE TO GENERAL RAILWAY SIGNAL COMPANY, OF GATES, NEW YORK, A CORPORATION OF NEW YORK.

MOTOR FOR OPERATING RAILWAY-SIGNALS.

1,162,695.

Specification of Letters Patent.

Patented Nov. 30, 1915.

Application filed July 29, 1911. Serial No. 641,266.

To all whom it may concern:

Be it known that I, WINTHROP K. HOWE, a citizen of the United States, and resident of the city of Rochester, in the county of Monroe and State of New York, have invented a new and useful Motor for Operating Railway-Signals, of which the following is a specification.

This invention relates to motors for operating railway signals, particularly to the semaphore type which are operated by means of rotary electric motors. In devices of this kind it is necessary that the semaphore move rapidly from the position indicating danger to either of the other two usual positions denoting caution and full clear. Such rapidity is attained by the consumption of relatively large amounts of electric current but in order to secure economy it is desirable, and in fact, almost necessary to reduce the amount of current consumed by the motor when holding the signal in the set position. To secure this economy, three general methods have heretofore been known. First: When the semaphore was in the set position, current was cut off from the motor and applied to a magnet, this magnet operating a brake on the motor shaft itself or on some part of the gearing connecting the motor shaft with the semaphore so as to prevent reverse movement and thus hold the semaphore in the set position. Second: This magnet was made to operate a latch commonly called a "slot" which was so arranged as to prevent the reverse movement and hold the semaphore in the set position.

Some of the early patents have shown semaphore signals operated and held by the energized motor without the use of either the brake magnet or the slot, but as is well known when an electric motor is brought to rest and its energization is maintained current increases to a point very much in excess of that which was required to set the semaphore, the reason for this is, as is well known, that when a motor is at rest, although energized, there is no counter-electromotive force tending to reduce the flow of current through the motor; when a motor is running there is a counter-electromotive force which, together with the resistance of the motor automatically limits the flow of current through the motor to that necessary

to do the work required of it, if, however, the motor is brought to rest and the voltage continues to be applied the counter-electromotive force mentioned, ceases, and the current increases very greatly, or in other words, is then limited only by the resistance of the motor. In order to hold a semaphore in the set position by the use of the armature of the motor alone it was necessary to adopt the third general method, to wit: the energization with a resistance in series with the motor circuit when the semaphore reached the set position thus decreasing the current flow to an economical point. The third general method mentioned, has, however, in practice been found subject to several defects, the most troublesome of which is the tendency of the semaphore to "drift," that is to say, the inability of the motor to retain the semaphore fixed in one position. This defect is especially noticeable when a three position signal is employed and an attempt is made to hold the signal in the caution position by the armature.

In order to overcome the defects incident to prior constructions and to construct a signal mechanism by which a semaphore is not only moved to the set position but held fixedly in such position by the action of the motor alone, advantage has been taken of what are technically known as "locking points." These "locking points" occur when the right number of slots are chosen and placed with reference to the pole pieces; the "locking points" above mentioned are merely a result of magnetic attraction which tends to hold the armature in a given position and to prevent movement in either direction. By a suitable design these "locking points" become very pronounced, particularly when the magnetic flux is increased.

In the drawings accompanying this application and in which like reference characters denote like parts, Figure 1, is a part front elevation of a two position semaphore signal and operating mechanism, together with a diagram of the circuit for such a signal. Fig. 2, is a diagrammatic illustration of the motor and circuits for a three position semaphore signal. Fig. 3, is a diagrammatic illustration of a construction to illustrate the locking points.

In the embodiment of my invention shown

in Fig. 1, 1 designates a signal pole to which is attached the mechanism case 2, there being a shaft 3 journaled in the mechanism case and having rigidly attached thereto casting 4 which bears the blade 5. 6 designates a sector rigidly attached to the shaft 3, and adapted to abut against the stop 7 when the signal indicates danger as is shown in the figure and adapted to abut against the stop 8 when the signal indicates clear. A movement from danger to clear is produced through the gearing 9, 10, 11, 12 and 13. The spur gear 13 is attached to a shaft 14 to which is also attached the armature 15 which revolves between poles 16, 17, 77 and 78 which have wound upon them the coils 18, 19, 20 and 21. The two coils 18 and 21 constituting the operating coils and the coils 19 and 20 constituting together with the coils 18 and 21 the retaining coils for holding the armature, the gearing and the semaphore in a moved position. 22 designates a drum of insulating material which is rigidly attached to the shaft 3 and consequently revolves with it and with the semaphore casting 4. On the periphery of the drum 22 is fastened the metallic strip 23 which, in the normal position of the semaphore as shown has the two springs 25 and 26 bearing thereon, but is of such length that when the signal is in the clear position it does not form a metallic bridge from brush 26 to brush 25. 27 designates a source of current here shown as a battery; 28 designates a metallic arm for connecting wires 29 and 30. When connection is closed between wires 29 and 30 a current flows in the following path: positive terminal of battery 27, wire 29, arm 28, wire 30, wire 31, brush 26, strip 23, brush 25, wire 32, wire 33, coil 18, wire 39, brush 38, armature 15, brush 34, wire 35, coil 21, and wire 36 to the negative terminal of the battery. The current in the above traced path causes the rotation of the armature and the movement of the signal to the clear position at which point sector 6 abuts the stop 8. Just before the signal reaches the clear position strip 23 passes from under brush 25 thereby breaking the operating circuit to the motor and thereupon current flows in the following path solely: positive terminal of the battery 27, wire 29, arm 28, wire 30, wire 37, coil 20, wire 38, coil 19, wire 40, wire 33, coil 18, wire 39, brush 33, armature 15, brush 34, wire 35, coil 21, and wire 36 to the negative terminal of the battery. The current in the above traced path is very much less in quantity than the current which flowed during the operation of the motor, for the coils 19 and 20 are formed of a very large number of turns of small wire and so offer considerable resistance but the design and ratio between the coils upon the poles of the motor is such, that sufficient current will flow to generate sufficient magnetic flux

to prevent the armature from being rotated backwardly by the weight of the semaphore casting 4.

In holding the semaphore in the clear position by the passage of current through the retaining circuit heretofore described, the motor is greatly aided by the presence of the slots 41 which extend longitudinally of the pole faces. By reference to Fig. 3, it will be seen that the distance between the slots 42 of the armature corresponds to the distance between the slots 41 of the pole faces. This construction creates a tendency when current flows through the operating fields and so produces a magnetic flux from pole to pole to hold the armature 15 locked in a position in which the slots of the armature and the slots of the pole faces coincide.

When all the poles of a motor are slotted to create the locking points, difficulties are liable to arise on account of the fact that the locking points may be made so pronounced that difficulty may be experienced in starting the motor, for which reason it is desirable to slot only one-half of the poles of a motor and to place the operating coils upon the poles which are not slotted and the retaining coils upon the slotted poles. Such a construction is shown in Fig. 2, in which, 43 and 45 designates the slotted poles and 44 and 46 the plain poles; the operating fields being designated by 47 and 48, retaining fields by 49 and 50; the armature being designated as in Fig. 1, by 15, and the brushes by 33 and 34. The circuit shown with this embodiment of my invention is adapted for use with a three position signal, the circuit breaker for the caution position being represented as a relay, designated by 53, the armature of which is designated by 54; the circuit breaker for controlling the full clear or 90° position of the signal being represented as a relay designated by 51 of which the armature is 52; 55 designates a metallic arm, movable with the signal, which bears upon a metallic strip 56 at the zero or danger position of the signal and remains in contact therewith during the movement of the signal until it almost reaches the caution or 45° position at which point it makes contact with strip 57 with which it remains in contact during the movement of the signal from caution or 45° position almost to the full clear or 90° position at which point it breaks contact with strip 57; 58 designates a metallic arm which makes contact with strip 59 at about the 45° or caution position of the signal and with strip 60 at about the 90° or full clear position of the signal. If relay armature 52 is dropped and relay armature 54 is picked up, current will flow in the following path; positive terminal of battery 27, wire 61, armature 54, wire 74, wire 62, wire 64, strip 56, arm 55, wire 65, wire 66, operating coil

48, wire 67, operating coil 47, wire 68, brush 33, armature 15, brush 34, and by wire 69 to the negative terminal of the battery 27. Current flowing in the above traced path 5 causes the armature 15 to rotate carrying with it any form of signal arm such as is shown by Fig. 1, connected thereto and will also move the arm 55 so that when the semaphore arm reaches the 45° position, the arm 10 will break contact with strip 56, thus cutting off operating current from the motor, but at the same time or just before, arm 58 makes contact with strip 59 so that current flows from the source in the following path: 15 battery 27, wire 61, armature 54, wire 74, wire 62, wire 75, strip 59, arm 58, wire 71, retaining coil 49, wire 72, retaining coil 50, wire 73, wire 66, operating coil 48, wire 67, operating coil 47, wire 68, brush 33, armature 15, brush 34 and wire 69 to the negative terminal of the battery. The current in the above traced path passing through the retaining coils 49 and 50 strongly energizes poles 43 and 45 and by reason of the locking 20 points formed due to the slotting of the pole faces, the armature is held fixedly in the moved position with no tendency to drift, at the same time the current flowing is materially reduced as the retaining coils 49 and 25 50 being composed of a large number of turns of small wire offer a considerable resistance to the flow of current. If the armature 52 should be raised while the signal was in the position to which it had been 30 moved by the current flowing in the above traced path, another circuit would be formed as follows: positive terminal of battery 27, wire 61, armature 54, wire 74, wire 76, armature 52, wire 63, strip 57, arm 55 to wire 35 65 and then through the same path which the operating current, as previously described passed, causing the armature to again rotate and move the semaphore to the full clear or 90° position at which time the arm 58 would make contact with strip 60 and the current from battery 27 would flow 40 to wire 70, and then to strip 60, arm 58 to wire 71 instead of from wire 63 to strip 57, as at the full clear or 90° position of the signal, the arm 55 could break contact with strip 57. The current flowing to wire 71 45 from the battery 27 would flow through the retaining circuit heretofore described and hold the semaphore in the moved position. 50 It is to be observed that a three position signal can have no stop against which it abuts when moved to the 45° position, for which reason it is very essential that a motor 55 designed for operating a signal and retaining a signal in the moved position should be constructed with locking points, for if an attempt is made to operate a signal by a motor and to also retain the signal in the moved position by the same motor 60 merely by the insertion of a resistance in

series therewith when the semaphore reaches the caution position, it will be found that on account of the varying torque on the semaphore shaft due principally to accumulations of snow and ice upon the semaphore 70 in winter, that great difficulty will be experienced in holding the signal fixedly in a certain position. When the motor is so designed to have locking points, as herein described, a semaphore can be held without 75 movement or drift at the 45° position as accurately as it can be held against the stop in the full clear or 90° position, for the presence of the locking points causes the armature when it comes to rest to stay at 80 rest accurately in the desired position.

This application is a continuation in part of my prior application Serial No. 493,216, filed April 30, 1909.

Having thus explained the principle of 85 my invention and described a particular specific embodiment thereof, what I claim as new and desire to secure by Letters Patent, is:

1. A motor, consisting of an armature and 90 field magnets having windings, said armature and field magnets constructed with longitudinal peripheral slots, the slots of said armature being spaced the same angular distance apart as the slots in said field magnets, 95 and means for altering the strength of the current flowing through said windings and thereby producing motion or rest of said armature.

2. In a motor, a rotary member formed 100 of magnetic material and having longitudinal slots, a fixed member formed of magnetic material, and having longitudinal slots spaced the same angular distance apart as the slots in the rotary member, and means 105 for producing separate magnetic fluxes in said rotary and said fixed members of variable intensity, thereby producing motion or rest of said rotary member against a counter-torque.

3. In a motor, a rotary member formed of 110 magnetic material and having a substantially circular periphery and longitudinal slots therein, a fixed member formed of magnetic material and having substantially 115 circular faces in proximity to the periphery of the rotary member and longitudinal slots therein, means for producing separate magnetic fluxes in said rotary and fixed members of variable intensity, thereby producing 120 motion or rest of said rotary member against a counter-torque.

4. In a motor, a rotatable member having longitudinal slots in its periphery, a fixed member formed with an aperture therein in 125 which the rotary member may revolve, and formed with longitudinal slots facing said aperture, means to produce a magnetic flux in said fixed and rotary members by energy 130 from an external source and means to pro-

- duce a magnetic flux in the same members at any predetermined point in the movement of said rotary member with less energy consumption than produced the first said flux.
5. 5. A motor, consisting of an armature and a plurality of pairs of diametrically opposite field magnets each pair having connected windings; an armature; connections controlling energy from a source to the armature, 10 means operated by the motor whereby the armature and the windings of one pair of field magnets are at times connected in series with each other and in circuit with the source and whereby at times the armature 15 and the windings of the said one pair are at times connected in series with each other and in series with the windings of another pair of field magnets and in circuit with the source.
20. 6. In a controller, in combination: a rotatable armature formed with longitudinal slots in its periphery; conductors on said armature; field electromagnets mounted adjacent the armature and having cores with 25 smooth faces toward the armature for producing a magnetic flux therein; means connecting the conductors for causing rotation when the field electromagnets and the said conductors are energized; holding electromagnets adjacent the armature and having 30 cores with faces toward the armature formed with longitudinal slots having the same angular pitch as the slots formed in the armature for producing a magnetic flux therein; 35 said holding electromagnets preventing rotation of the armature when energized in a circuit in series with the said field electromagnets and the said conductors; means for connecting said conductors and the field electromagnets in a circuit with a source of 40 energy and means for connecting the holding electromagnets in a circuit in series with the field electromagnets and the said conductors and a source of energy.
7. In a controller, in combination; an electric motor having field electromagnets with smooth faced pole pieces and a rotatable armature formed with longitudinal slots in its periphery; holding electromagnets adjacent the armature and having cores with 45 faces toward the armature formed with longitudinal slots having the same angular pitch as the slots formed in the armature for producing a magnetic flux therein, said holding electromagnets preventing rotation of 50 the armature when energized in a circuit in series with the field electromagnets and the armature; means for completing a circuit including the field electromagnets and the armature for operating the motor and means 55 after the armature has rotated a predetermined angular distance for completing a circuit including the holding electromagnets in series with the armature and the field electromagnets and a source of energy.
